UNITED STATES PATENT OFFICE.

UBALD HEBERT, OF MANCHESTER, NEW HAMPSHIRE.

FEELER MECHANISM FOR AUTOMATIC FILLING-REPLENISHING LOOMS.

1,151,010.

Specification of Letters Patent. Patented Aug. 24, 1915.

Application filed April 9, 1914. Serial No. 830,784.

To all whom it may concern:

Be it known that I, UBALD HEBERT, a citizen of the United States, residing at Manchester, New Hampshire, have invented an improvement in Feeler Mechanism for Automatic Filling-Replenishing Looms, of which the following description, in connection with the accompanying drawing, is a specification, like characters on the drawing representing like parts.

This invention has for its object the production of a novel means for detecting substantial exhaustion of filling in the active shuttle of the loom and thereupon automatically effecting a change in the operation of the loom, such as the automatic replenishment of the filling, or the automatic stoppage of the loom.

In the preferred embodiment of the invention illustrated herein this invention is shown as applied to a loom of the Northrop type which has been adapted to use bobbins having slotted barrels into which the feeler arm is projected when the filling is so far unwound from the bobbin barrel as to uncover said slot or a portion thereof. In such automatic filling replenishing looms the detection by the feeler of absence of filling upon the filling carrier usually causes a movable member to be positioned in the path of the shuttle box or some other element carried by the lay which causes the actuation of means to initiate the operation of the transfer mechanism. In such looms a careful and accurate adjustment of the feeling mechanism is required to maintain the same in operative condition and even when the parts are properly adjusted transfer is sometimes effected prematurely by reason of the vigorous action of the lay.

One object of the invention therefore is to provide a simple but very sensitive mechanism for detection of substantial exhaustion of filling which will not require constant adjustment but which will act with certainty.

Another of the objects of the invention is to provide mechanism adapted to the Northrop type of loom through which the actuation of the transfer mechanism is initiated by mechanism other than the movement of the lay preferably by means actuated from a cam upon the take up shaft of the loom whereby the likelihood of premature actuation of the transfer mechanism is avoided.

Other objects of the invention and the nature thereof will more fully appear from

the following description and accompanying drawing and will be particularly pointed out in the annexed claims.

In the drawings: Figure 1 is a plan view of a portion of a loom embodying my invention, Fig. 2 is a vertical side elevation illustrating the relative position of the feeler mechanism, the transmitter and a preferred means for actuating the same, Fig. 3 is a detail view of the feeler and the means for supporting the same.

In the drawings, Fig. 1 illustrates the ordinary lay 1, having a shuttle box 2 inclosing a shuttle 3 provided with a suitable filling carrier 4, preferably a bobbin having a slot 5 in its barrel near the base thereof, the shuttle and shuttle box being provided respectively with slots 6 and 7 through which the end of the feeler is adapted to pass. The lay is mounted in the usual manner and the shuttle carried thereby is adapted to be replenished from a battery 8 from which the filling carrier is delivered by a transfer arm 9 which is actuated through a controlling rock shaft 10 in the usual manner.

The loom is provided with the usual filling fork mechanism 12 and weft hammer 13 for operating the same upon detection of failure or absence of filling, the weft hammer being provided with a projection or bracket 14 adapted to engage a positioned end of a latch 15 which is pivotally mounted upon an arm 16 projecting upwardly from the controlling rock shaft 10.

The breast beam is preferably provided with the usual extension 17 having a notched slot 18 to receive a shipper lever 19, a lever 20 mounted upon a pivot 21 being adapted to disengage the shipper from the notch through the automatic operation of the stop mechanism in the usual manner.

As illustrated in the drawing a transmitter 25 is provided which is adapted to raise the latch 15 into engagement with a notch in the vibrating actuator or weft hammer as is the case in the ordinary construction of the Northrop automatic loom but the character of the transmitting lever as embodied in my invention is modified and the means for actuating it are derived from a suitable constantly moving part of the loom other than the lay, such as a cam upon the takeup shaft, the operation of the transmitter being merely controlled by the action of the feeler.

In the preferred form of invention illustrated herein the one end of the transmit-

25 extends beneath the latch 15 in the usual manner but its opposite end is pivoted upon a lug 26 projecting laterally from a bracket 27 which is rigidly secured to a lug 28 extending upwardly from the extension 17, suitable lugs 29, 30 serving to guide the free end of said transmitter. The transmitter is provided intermediate of its ends with a laterally projecting stud 32 upon

10 which is mounted a vibrating member consisting of a hub 33 having oppositely extending arms 34 and 35 the end of the arm 34 being connected by a link 36, preferably adjustable in length, to a pivotally mounted 15 arm 37 which is adapted to be engaged by a cam 38 mounted upon one of the constantly rotating shafts of the machine, preferably the take-up shaft 39.

The constant reciprocation given to the 20 link 36 causes the vibrating member normally to oscillate idly upon its pivot 32, but when the end of the free arm 35 is restrained the reciprocating link causes a bodily movement of the lever raising the pivot 25 32 and thereby actuating the transmitter 25 to position the latch 15 in the path of the vibrating actuator or weft hammer. Means for thus restraining the movement of the free end of the vibrator are preferably controlled from the feeler in the following 30 manner: The feeler 40 preferably is slidably mounted in a bearing 41 extending laterally from a bracket 42 which is adjustably secured to the extension 17, said bracket being provided at its lower end with an ear 43 having a stud 45 upon which an arm 44 is pivotally mounted. The arm 44 is pivotally attached at its upper end to the feeler 40 and is provided at its lower end with a lateral arm having a counterweight 46 which 40 normally holds the feeler in feeling position. A suitably cushioned lug 47 projecting from the bracket 42 limits the movement of the arm 44 in one direction and a resilient member 48 preferably constructed of heavy leather serves to arrest the movement of the arm 44 when thrust forward by the feeler by its engagement with the filling on the bobbin. The arm 44 is provided with 45 a laterally extending ledge 49 which is held normally beneath the end 35 of the vibrator, but is withdrawn from said position whenever the arm 44 is rocked by the feeler upon its engagement with the filling carrier as the 50 lay beats up.

When the filling has become sufficiently exhausted to expose the slot 5 in the bobbin barrel the feeler 40 will not be pressed forward and the ledge 48 will remain in the 60 path of the free end 35 of the vibrator thus restraining the downward movement thereof. By reason of this restraint the vibrator will be raised bodily by the action of the cam 38 and will cause the transmitter 25 to 65 be moved about its pivot raising the end

thereof and with it the latch 15 into the path of the vibrating controller or weft hammer. Upon the forward movement of the latter the arm 16 of the shaft 10 will be forced forward thus positioning the dog of the 70 transfer mechanism in the path of the lay in the usual manner to cause the transfer arm to deliver a new filling carrier from the hopper into the shuttle.

It will be observed that by reason of the 75 fact that the feeler merely causes the vibration of the pivoted arm 44 which is provided with a relatively wide ledge 49 and of the further fact that a considerable amplitude of movement is permitted when the feeler 80 enters the slot in the bobbin, the delicate adjustments which have been heretofore necessary are eliminated and the constant attention required thereby avoided.

It will be obvious that if desired the 85 mechanism above described may be caused to coöperate with the shipping mechanism of the loom in such a manner as to cause the stoppage of the loom upon the detection of exhaustion of filling.

It will also be obvious that the vibrator 34, 35 may be actuated from any rotatable shaft of the loom and that its actuation from the take up shaft as disclosed herein is merely illustrative of a convenient means, 95 probably the most convenient means, for actuating the same.

It is to be understood therefore that the embodiment of the invention herein is merely illustrative and is not restrictive and 100 that it may be embodied in various other forms of mechanism.

Having thus described my invention what I claim as new and desire to secure by Letters Patent is:

1. In an automatic filling replenishing loom, transferring mechanism, means for actuating the same including a vibrating member actuated from the take-up shaft of the loom to vibrate in a vertical plane, a 110 feeler, a counterweighted pivotally mounted member connected thereto, having means adapted upon detection of absence of filling by said feeler to arrest said vibrating member and thereby initiate the actuation of the 115 transfer mechanism.

2. In an automatic filling replenishing loom, transferring mechanism including a latch adapted to be positioned in the path of a vibrating actuator, a transmitter, a vibrating member pivotally mounted thereon, a feeler, an oscillating arm controlled by said feeler and having a member adapted upon detection of absence of filling to engage said vibrating member and thereby cause the actuation of the transmitter to position the latch in the path of the vibrating actuator whereby the actuation of the transferring mechanism will be initiated.

3. In an automatic filling replenishing 130

5 loom, transferring mechanism including a latch adapted to be positioned in the path of a vibrating actuator, positioning means for said latch comprising a transmitter, a vibrating member pivotally mounted thereon, a feeler and means controlled by said feeler adapted upon detection of an absence of filling to engage said vibrating member and thereby to cause the positioning of the latch 10 in the path of the vibrating actuator to cause the actuation of the transferring mechanism.

4. In an automatic filling replenishing loom transferring mechanism and means for actuating the same comprising a controlling 15 rock shaft, a latch carried thereby adapted to be positioned in the path of a vibrating actuator, a transmitter for positioning the same, a vibrating member pivoted thereon having one end actuated by a suitable cam, 20 a feeler, and means controlled thereby adapted upon detection of absence of filling to restrain the vibration of the other end of said vibrating member and thereby cause bodily movement thereof to actuate the transferer 25 to cause the positioning of the latch in the path of the vibrating actuator.

5. In an automatic filling replenishing loom, transferring mechanism including a controlling rock shaft, a latch carried there- 30 by adapted to be positioned in the path of a vibrating actuator, a transmitter for positioning said latch, a vibrating member pivoted upon said transmitter, means actuated by the take-up shaft of the loom connected 35 to one end of said vibrating member, a feeler and means controlled thereby adapted to be positioned in the path of the other end of said vibrating member upon detection of absence of filling to cause bodily movement 40 thereof to actuate the transmitter to cause the positioning of the latch in the path of the vibrating actuator.

6. In an automatic filling replenishing loom transferring mechanism, means for 45 actuating the same comprising a controlling rock shaft, a latch carried thereby adapted to be positioned in the path of a member carried by the weft hammer, a transmitter pivotally supported at one end and engag- 50 ing said latch at its opposite end, a vibrat- 55 ing member pivotally mounted upon said transmitter, intermediate of its ends, means attached to one end of said vibrating mem- ber for actuating the same, a feeler mounted upon an arm having a projection adapted 60 upon detection of absence of filling to be positioned beneath the free end of said vibrat- 65 ing member to cause bodily movement there- of to actuate said transmitter and thereby to position the end of the latch in the path of said weft hammer.

7. In an automatic filling replenishing

loom, transferring mechanism comprising a transfer arm, a dog carried thereby adapted to be positioned in the path of the bunter of 65 the lay, a controlling rock shaft for said dog, an arm carried thereby, a latch pivotally mounted upon said arm adapted to be positioned in the path of a member carried by the weft hammer, a transmitter having 70 one end extending beneath said latch and pivotally mounted at its opposite end, a vibrat- 75 ing member pivotally mounted upon said lever, means connected to one end of said vibrator for continuously vibrating the same, a feeler, an arm actuated thereby having a ledge adapted upon detection by said feeler of absence of filling to enter beneath the free end of the vibrating member and restrain the movement thereof whereby bodily movement of said vibrating member will be produced which will actuate the transmitter to position the end of said latch in the path of the weft hammer and thereby cause the action of the transferring mecha- 80 nism.

8. In an automatic filling replenishing loom, transferring mechanism including a latch adapted to be positioned in the path of a vibrating actuator, a transmitter, a vibrat- 90 ing member pivotally mounted thereon, a feeler pivotally mounted upon a counter- weighted arm and adapted normally to engage the filling upon the bobbin and to enter a slot in the bobbin upon substantial ex- 95 haustion of filling, a ledge upon said counterweighted arm adapted to be positioned in the path of said vibrating member when the feeler enters the slot in the bobbin and there- 100 by to cause the actuation of the transmitter to position the latch in the path of the vi- brating actuator.

9. In an automatic filling replenishing loom, transferring mechanism including a controller shaft and latch thereon adapted to 105 be positioned in the path of a vibrating actuator, a transmitter, a vibrating member pivotally mounted thereon, an adjustable feeler stand, a feeler, a member controlled by said feeler having a ledge adapted, upon detec- 110 tion of absence of filling by said feeler to arrest said vibrating member and thereby cause the actuation of the transmitter to position the latch in the path of the vibrating actuator whereby the actuation of transfer- 115 ring mechanism will be initiated.

In testimony whereof, I have signed my name to this specification, in the presence of two subscribing witnesses.
